UNITED STATES PATENT OFFICE.

ELMER CLAUDE SHERWOOD, OF NEW YORK, N. Y.

REGISTER-OPERATING MECHANISM AND SEAT.

1,248,180.

Specification of Letters Patent. Patented Nov. 27, 1917.

Application filed May 20, 1915, Serial No. 29,412. Renewed April 24, 1917. Serial No. 164,279.

To all whom it may concern:

Be it known that I, ELMER CLAUDE SHERWOOD, a citizen of the United States, and resident of the borough of Manhattan, city, 5 county, and State of New York, have invented certain new and useful Improvements in Register-Operating Mechanisms and Seats, of which the following is a specification.

0 The device, the subject of this invention may appear to be a combination but it is not my intention to broadly claim the means for operating a fare register as I am aware that registers have been operated by means 5 of a floor pin or plug prior to my development of this invention.

Here, however I show a construction including parts arranged in definite relation, parts which although in themselves known, 0 here develop new functions and new advantages.

This invention is particularly adapted for use with center entrance street cars. Cars wherein the conductor or collector is stationed at one particular point, a point which all of the passengers must pass upon entering or leaving the car and my device is intended to make the work of the conductor or collector less arduous and yet as satisfactory.

The construction and advantages of my invention will be set forth as this specification progresses.

The following is what I consider the best means of carrying out this invention, and

The accompanying drawings form a part of this specification, in which:

Figure 1 is a side elevation of my device, the dotted lines indicating the changed position.

Fig. 2 is an elevation taken in the direction of the arrow in Fig. 1.

Fig. 3 is a plan view of the saddle.

Similar reference numerals indicate like parts in all the figures where they appear.

At 1, I have indicated a rod or shaft suspended under the car floor by means of bearing blocks indicated at 2, this rod is the means by which a fare register is operated and the register may be arranged at any desirable point within the car or otherwise.

To operate the register it is necessary to partially rotate the shaft 1 and to accomplish this I arrange a crank lever upon the shaft 1 and secure it thereon, the lever has two extending parts or arms as indicated

at 3 and 4 and as it is desirable that the shaft 1 shall always operate in a given direction I arrange a bell crank lever 5 adjacent to the arm 4 and pivotally supported as indicated at 6. The bell crank has an extending end 7 which will receive an impulse or pressure from an operating means and the connection between the bell crank 5 and arm 4 is by means of a pin 8 and slot 9 for a 65 purpose that shall appear obvious.

The floor of the car is indicated at 10 and 11, 10 being the ordinary wooden flooring and 11 the protective casing of cement or other material providing a wearing surface 70 of high resistance.

Through the floor I provide a plurality of perforations as indicated at 12 and 13, the perforation 12 being immediately over the arm 3, of the register shaft 1, and the 75 perforation 13 immediately over the free end of the bell crank lever. It is quite obvious then that when a plug or pin or other device is passed into and through one of the perforations 12 or 13 an operating impulse 80 will be given to the lever directly under the perforation and will by the mechanism provided impart a partial rotation to the shaft 1.

I provide a pin as indicated at 14 which 85 may receive the pressure of the foot of the conductor, in Fig. 1 this pin is shown as arranged in the perforation 12 but I desire to call attention to the fact that this pin may be transferred from the perforation 12 to the 90 perforation 13 and back as often as requirements demand.

At 15 I indicate a saddle of peculiar shape as shown in Fig. 3, this saddle is provided with a shaft or staff 16, which is received 95 in a tubular socket or pipe end 17, the socket is a portion of a pipe bent as indicated in Fig. 1, the part 17 being vertical the portion 18 arranged at an angle and the portion 19 again vertical. At the lower end of 100 the part 19 of the pipe I fit a flange 20 and into this flange I secure a pin 21 entering the perforation 13 in the floor and although held firmly therein not permanently secured.

Under the saddle 15 and secured to the angular portion 18 of the seat supporting pipe is an inverted V shaped member 22, made of strap iron or other suitable material and secured by means of a rivet 24, or 110 by other means to the seat supporting pipe. The V shaped member extends from the

pipe to the upper surface of the floor and has its ends bent inward and joined thus providing an additional support for the saddle and a guard for the foot lever.

- 5 As indicated at 25 in Fig. 2 I may provide a slot in the vertical portion 19 of the seat supporting pipe and quite close to the lower end thereof, in this slot I arrange a lever 26, which extends outward in the direction of the saddle and is then turned so that the flat portion 27 of the lever is on a horizontal plane, this flat portion extends beyond the floor plug or pin 14, and is then bent upward to produce a pressure receiving arm 28, this arm which should not extend beyond the line of one side of the brace 22, is adapted to receive the pressure from the foot of the operator, and as it is pivoted as indicated at 29 the pressure of the 10 operator's foot will depress this lever 26, the pin 14 and the lever 3 thus partially rotating the shaft 1.

I have previously indicated that my device might be changed from side to side 25 and I desire to call attention to the fact that when the pin 14 is changed from one perforation to another, the seat retaining or securing pin 21 is also changed so that it will be arranged in the perforation not occupied by the pin 14, the dotted lines 30 indicate the position of the seat supporting means when the pin 21 is arranged in the perforation 12, and the dotted lines 31 call attention to the fact that the pin 21 does not extend through the floor to a distance sufficient to cause an operation of the fare 35 register shaft or to interfere with the free operation thereof or the parts which are provided for operating.

40 The saddle 15 supported by a pin 16 entering the socket 17 may be rotatable and thus not interfere with the free movement of the body of the operator.

From the description of the construction 45 the operation of my device is quite obvious, I desire however to indicate certain advantages.

First the restful position of the operator, second the convenience of the position of 50 the parts, third the protection of the pin 14 which cannot be inadvertently operated

by passengers entering or leaving the car, fourth the fact that both of the perforations through the floor are constantly filled thus preventing the passage therethrough of foreign material which might interfere with the operation of the register operating mechanism. 55

The general shape of my device may be changed at will and I may make the member 60 17, 18, 19 solid by modifying the means for retaining the saddle.

The shape of the support 22 may also be changed as may the shape of the saddle 15 and other modifications may be made within the scope of the appended claims but I prefer the whole as shown and described. 65

Having carefully and fully described my invention what I claim and desire to secure by Letters Patent is:— 70

1. The combination with a car floor having a plurality of perforations therethrough, of a duplex lever arranged under said floor and adapted to operate a register mechanism, an operating pin adapted to pass 75 through one said perforation and an angularly arranged tubular member provided with a pin adapted to enter another perforation, said first mentioned pin engaging said lever, and said second mentioned pin being retained away from said lever in combination with a foot lever upon said angularly disposed member, and a support upon said angular member for guarding the foot lever, all combined for joint operation as 80 herein specified.

2. The combination with a car floor provided with a plurality of perforations of a fare register operating mechanism under said floor, a saddle support adapted to be 85 received in one said perforation, an operating pin adapted to be received into another said perforation, and a lever from said saddle support to said operating pin for the purpose set forth. 90

Signed at New York city, in the county and State of New York this 6th day of May, 1915.

ELMER CLAUDE SHERWOOD.
